KALMAN VON KANDO, OF VADO LIGURE, ITALY, ASSIGNOR, BY MESNE ASSIGNMENTS, TO WESTINGHOUSE ELECTRIC & MANUFACTURING COMPANY, OF EAST PITTSBURGH, PENNSYLVANIA, A CORPORATION OF PENNSYLVANIA.

ELECTRICAL INSULATOR.

1,376,486.

Specification of Letters Patent. Patented May 3, 1921.

Application filed December 9, 1914. Serial No. 876,382.

To all whom it may concern:

Be it known that I, KALMAN VON KANDO, a subject of the Emperor of Austria and of the King of Hungary, and a resident of 5 Vado Ligure, in the Kingdom of Italy, have invented a new and useful Improvement in Electrical Insulators, of which the following is a specification.

My invention relates to electrical insulators and in particular to insulators for supporting the contact wires of electric rail- 10 ways.

One object of my invention is to provide an improved means for anchoring a bolt 15 within a recessed insulator.

Another object of my invention is to pro- 20 vide an insulator which will positively support the suspended contact wire even though the insulator becomes broken.

A further object of my invention is to provide an improved form of insulator of small size and relatively great strength.

When a high voltage is to be employed in an electric railway system, the insulators 25 for supporting the contact wire must be made of a material having considerable strength and a high resistance. Porcelain, by reason of its strength and superior insulating properties, is recommended as prac- 30 tically the best material for this purpose.

The low co-efficient of expansion by heat of porcelain makes it difficult to secure the metal bolts which support the trolley conductors. Where cement is used for secur- 35 ing the bolts in porcelain insulators, a moderate rise in temperature produces sufficient expansion of the metal bolt and the cement to break the porcelain because the expansion of iron and of cement is many times as 40 great as that of porcelain.

According to my invention I secure the metal bolt to the porcelain insulator by means of an improved form of anchor em- 45 bedded in an easily fusible metal. The por- celain is made substantially uniform in thickness and is inclosed by a metal shell having a restricted portion which is of smaller diameter than the body of metal in which the head of the bolt is embedded in 50 order that the bolt cannot become disengaged from the metal shell and thereby re- lease the contact wire from its support even though the porcelain should become broken.

Figure 1 of the accompanying drawing is

a central sectional view of an insulator em- 55 bodying my invention; Fig. 2 is a sectional view on the line II—II of Fig. 1 and Fig. 3 is a plan view of the bolt-anchoring means shown in Fig. 1.

The device shown in the drawing com- 60 prises a porcelain insulator 1, an improved anchor member 2, a conductor-suspending bolt 3 which is removably secured to the member 2, an interposed filling material 4 and a metallic casing 5.

The porcelain insulator 1 is of substan- 65 tially bell-shape, has a constrained waist portion and is illustrated as having walls of a uniform thickness. The anchor mem- 70 ber 2, which is of elliptical form as best shown in Fig. 3, is sufficiently narrow in one direction to be longitudinally admitted through the constrained opening of the por- celain 1 and has a diameter in another di- 75 rection that is larger than the diameter of the opening through which it is admitted. A screw threaded aperture is provided in the center of the member 2 for suitably se- 80 curing the same to the bolt 3.

The filling material 4 is preferably a 80 fusible alloy (such, for instance, as Rose's metal) the melting point of which is very low but still much above the maximum tem- 85 perature likely to be experienced in prac- tice and which contracts on solidifying. Af- 90 ter solidification and cooling the mass of the parts 2, 3 and 4 contracts to a greater ex- 95 tent than the porcelain insulator 1 and, as a result, a space is formed between the mass 4 and the porcelain 1 which is sufficient to 100 permit of a free expansion of the parts 2, 3 and 4 without breaking the porcelain.

The metallic casing 5, by which the insu- 105 lator may be readily suspended from strain wires or the like, is comprised of two parts 95 which are secured together by the bolts 6. The space between the members 1 and 5 is filled with a cement 7. The casing 5 has a restricted portion 8, the opening in which is smaller than the mass of securing metal 100 4, in order that the bolt 3 will not become disengaged from the metallic shell 5 and thereby release the contact wire from its support if the porcelain 1 should become broken.

To assemble such an insulator as I have de- 105 scribed, the anchor member 2 is first longi- tudinally inserted within the porcelain 1 and

the bolt 3 is secured thereto. The space between the members 1 and 2 and 3 is then filled with the material 4. The two-piece casing 5 is positioned around the porcelain 1 and secured thereto by bolts 6 and an interposed layer of cement 7.

By employing the bell-shaped porcelain member shown in the drawing, the supporting bolt 3 may be of relatively large 10 cross-section and short length which provides a very compact and strong insulator.

Although I have described my invention as embodied in a simple and preferred form of contact-wire insulator, it is not necessarily so limited and may be incorporated in 15 a great many different types of insulators. I desire, therefore, that only such limitations shall be imposed as are set forth in the appended claims.

20 I claim as my invention:

1. The combination with a hollow insulator having a constricted opening, of an elliptical anchor member the larger diameter of which is greater than the largest 25 diameter of the said opening, a bolt adapted to extend through said opening and be secured to said anchor member and filling material interposed between said insulator and said bolt and anchor member.

30 2. The combination with a hollow bell-shaped insulator having a constricted opening, of an elliptical anchor member that is adapted to be inserted through said opening and having the larger diameter thereof 35 greater than the largest diameter of said opening, a bolt adapted to be secured to said anchor and filling material interposed between said anchor and said insulator.

3. The combination with a bell-shaped 40 insulator having walls of a substantially uniform thickness and a constricted waist portion, of an elliptical anchor member adapted to be inserted only longitudinally within said insulator, a bolt extending into 45 said insulator and secured to said anchor member, a metallic casing surrounding the upper portion of said insulator and secured

thereto, and readily fusible metal surrounding said anchor member and said bolt and constituting a head for said bolt of larger 50 diameter than the waist portion of said insulator.

4. The combination with a hollow bell-shaped insulator having a restricted opening, a metallic casing surrounding the upper 55 portion of said insulator and flaring outwardly over the lower portion thereof, of an elliptical anchor member adapted to be inserted only longitudinally within said opening, a bolt extending through said opening and secured to said anchor member, and a filling substance for securing said bolt and anchor member in place.

5. The combination with a hollow bell-shaped insulator having a constricted waist 65 portion and a two-piece metallic casing surrounding said insulator and gripping the upper portion thereof, of an elliptical anchor member adapted to be inserted only longitudinally within the upper portion of 70 said insulator, a bolt adapted to be secured to said anchor member and an easily fusible metal for securing said anchor and said bolt within said insulator, the said body of fusible metal being of larger diameter than the 75 waist of said insulator.

6. The combination with a hollow insulator having a single constricted opening of circular form, of an anchor member having one diameter which is less than the diameter of said opening and another diameter which is greater than the diameter of said opening, a bolt adapted to extend through said opening and be secured to said anchor, and means for securing said bolt and anchor 85 within said insulator.

In testimony whereof I have hereunto subscribed my name this 28th day of October, 1914.

KALMAN von KANDO.
